UNITED STATES PATENT OFFICE.

ORRIN P. TALLEY, OF CHICAGO, ILLINOIS.

BUTTON.

No. 926,515.

Specification of Letters Patent.

Patented June 29, 1909.

Application filed April 20, 1907. Serial No. 369,356.

To all whom it may concern:

Be it known that I, ORRIN P. TALLEY, a citizen of the United States, and resident of Chicago, county of Cook, State of Illinois, have invented certain new and useful Improvements in Buttons, of which the following is a specification, and which are illustrated in the accompanying drawings, forming a part thereof.

10 The invention relates to buttons of that form adapted to be secured to a garment without sewing, and the object of the invention is to provide a button which may be firmly attached to a garment of any usual 15 thickness, and may, if desired, be subsequently removed without injury to the fabric from which the garment is composed.

The invention contemplates a button having securing means comprising two bodily 20 separable telescoping members, the inner member being a clasp, which when separated from the outer may be applied to a garment to which the button is to be attached, and which will be compressed to firmly grip the 25 fabric of the garment by the re-assembling of the parts, the head of the button being carried by the outer member.

The invention is exemplified in the structure to be hereinafter described, and illustrated in the accompanying drawings, in which,—

Figure 1 is a perspective view showing the inner member of the button-securing means in position upon a garment; Fig. 2 is similar 35 to Fig. 1, but shows the parts of the button assembled; Fig. 3 is a central vertical section showing the head of the button and the outer member of the securing means; Fig. 4 is a sectional detail viewed from the line 4—4 40 of Fig. 3; Fig. 5 is a central vertical section showing the inner member of the securing means; Fig. 6 is a sectional detail taken on the line 6—6 of Fig. 5; Fig. 7 is a plan view showing the blank of sheet-metal from 45 which the parts shown in Figs. 5 and 6 are formed; and Fig. 8 is a central vertical section showing the parts of the button assembled.

The head of the button is designated 10, 50 and, as shown in the drawings, it is of sheet-metal, and is provided with an apertured shank 11. For securing the button to a gar-

ment, two bodily separable telescoping members are provided, the outer member 12 taking the form of a yoke adapted to straddle 55 the marginal edge of the garment and made rigid by longitudinal ribs 13—14. The head 10 of the button is permanently secured to the yoke member 12, preferably by expanding a flange 15, which is turned outwardly 60 about an aperture 16 formed in one arm of the yoke, within the apertured shank 11 of the button.

A clasp 17 for securing the button to a garment is removably fitted within the yoke member 12. As shown, this clasp is of spring metal, and is formed from a blank, shown in Fig. 7, bent to the form of a V having a flaring or bell-shaped mouth. Prongs 18 and 19 are turned inwardly from each arm of the V, 70 and these prongs are preferably of such length that the ends of those extending from opposite sides of the V do not overlap when the clasp is in its expanded position, shown in Fig. 5, thus providing for an easy removal 75 from an application to the garment.

In use, the clasp 17 will be fitted over the marginal edge of a garment after the manner shown in Fig. 1 of the drawings, and the yoke member 12 carrying the head 10 of the button will be passed over the clasp, the arms of the latter being compressed by this assembling of the parts to cause the prongs 18—19 to firmly grip the fabric of the garment. A catch is provided for securing the yoke member 12 and clasp 17 in assembled position, and, as shown, this comprises a recess or aperture 20 formed in the clasp adjacent its outer end and a lug 21 turned inwardly from one arm of the yoke member 12 to engage the 85 recess 20. In order that the button may be easily removed from the garment, a portion 22 of the clasp 17 projects beyond the yoke member 12 when the parts are assembled, as most clearly shown in Fig. 8, to permit the 90 clasp to be compressed by the hand for releasing the parts 20—21 of the catch. When this has been done, the yoke member 12 carrying the head 10 of the button may be easily withdrawn from the clasp, and the latter will 95 then assume its expanded form, shown in Fig. 5, and may be removed from the garment without injuring the fabric from which it is 100 formed.

I claim as my invention,—

In combination, a V-shaped clip, the arms of the clip having inwardly-directed tines adjacent their outer ends, a rigid button-carrying yoke adapted to telescopically receive and compress the clip, the arms of the yoke, when the parts are in assembled position, being engaged with the arms of the clip be-

yond the location of the tines, and a catch for maintaining the parts in assembled position. 10

ORRIN P. TALLEY.
